UNITED STATES PATENT OFFICE.

LOUIS A. GABLE, OF HARRISBURG, PENNSYLVANIA.

DESIGN FOR A COMBINED TOOTH-CLEANER AND SUPPORT.

58,668.

Specification for Design.

Patented Aug. 9, 1921.

Application filed November 22, 1920. Serial No. 425,916. Term of patent 14 years.

To all whom it may concern:

Be it known that I, LOUIS A. GABLE, a citizen of the United States, residing at Harrisburg, in the county of Dauphin and State of Pennsylvania, have invented a new, original, and ornamental Design for a Combination Tooth-Cleaner and Support, of which the following is a specification, reference being had to the accompanying drawings, forming part thereof.

The figure is a perspective view of a combination tooth cleaner and support showing my new design.

I claim:

The ornamental design for a combined tooth cleaner and support as shown.

LOUIS A. GABLE.
